US00D968667S

(12) **United States Design Patent** (10) **Patent No.:** **US D968,667 S**
Liu et al. (45) **Date of Patent:** **** Nov. 1, 2022**

(54) **FLASHLIGHT**(71) Applicant: **Energizer Brands, LLC**, St. Louis, MO (US)(72) Inventors: **Bin Liu**, Ningbo (CN); **Melinda Yiu**, Kowloon (HK)(73) Assignee: **Energizer Brands, LLC**, St. Louis, MO (US)(**) Term: **15 Years**(21) Appl. No.: **29/755,413**(22) Filed: **Oct. 20, 2020**(51) LOC (13) Cl. ..... **26-02**(52) U.S. Cl. USPC ..... **D26/49**(58) **Field of Classification Search**

USPC D26/24, 37-52, 113, 118-119, 138
CPC F21Y 2115/10; F21Y 2113/13; F21Y 2103/10; F21Y 2101/00; F21Y 2107/40; F21Y 2105/10; F21Y 2105/18; F21Y 2113/00; F21Y 2113/10; F21Y 2113/17; F21Y 2113/20; F21L 4/005; F21L 4/027; F21L 4/085; F21L 4/08; F21L 4/045; F21L 4/00; F21L 4/02; F21L 4/022; F21L 4/04; F21L 4/025; F21L 13/00; F21L 14/02; F21L 2/00; F21V 23/0414; F21V 23/0428; F21V 21/0965; F21V 23/0421; F21V 15/01; F21V 21/0885; F21V 21/406; F21V 23/0407; F21V 23/06; F21V 33/0064; F21V 33/0084; F21V 14/025; F21V 23/003; F21V 23/04; F21V 14/065; F21V 21/084; F21V 21/08; F21V 21/30; F21V 23/0435; F21V 31/00; F21V 31/005; F21V 33/0076; F21V 33/008; F21V 5/006; F21V 7/0075; F21V 14/045; F21V 15/012; F21V 17/12; F21V 19/02; F21V 21/0816; F21V 21/0925; F21V 23/0464; F21V 23/0471; F21V 5/04; F21V 13/045; F21V 17/002; F21V 21/096; F21V 21/145; F21V 23/023;
